UNITED STATES PATENT OFFICE

JOHN A. BOYCE, OF CHICAGO, ILLINOIS

PRINTING MACHINE

Application filed August 16, 1927. Serial No. 213,276.

The present invention is directed to a rotary printing press employing cylinders each adapted to carry two semi-cylindric plates around the cylinder columns circumferential, the cylinders being of a length to perfect a two-page wide web or multiple thereof, with an exception presently to be noted.

The present invention is directed primarily to the provision of a supplement printing cylinder or cylinders adapted to be run either at full speed or half speed for the purpose of printing a two-page or a four-page supplement, or both a two-page and four-page supplement, and the arrangement is one which will permit the perfecting, folding and cutting of a newspaper in any number of pages constituting a multiple of two up to the full capacity of the machine. This result is attained by the employment of the regular cylinder or cylinders capable of being run at full speed in conjunction with a collecting mechanism located below the former, which arrangement permits the full speed cylinders to print alternately on continuously moving full speed webs, the text constituting the respective sections of a newspaper, and permits the half speed web running from the supplement cylinder to be cut into supplement lengths and introduced into every alternate length of the full speed web, so that the supplement pages will be included in one section only of the completed newspaper. This capacity in the machine of running the supplement cylinder or cylinders at half speed for the purpose of introducing two page supplement sheets into one section only of a collected newspaper, together with the further capacity of running the supplement cylinder or cylinders at full speed to provide for the introduction of two-page supplement sheets into each of the sections of the completed newspaper permits of the ready adjustment of the machine to print, collect, fold and deliver newspapers in any multiple of two up to the full capacity of the machine.

All of the cylinders being of a size to accommodate two plates around each cylinder columns circumferential, it is possible to plate each of the cylinders either with duplicate plates or with single plates around, depend-

ing upon the use or omission of collecting mechanism below the former, and this capacity for alternate plating, conjoined with the capacity for running the supplement cylinders either at full speed or half speed, enables the machine as a whole to be employed in the printing of newspapers either in book form or section form, so that the machine is adaptable to meet the varying requirements both as to size and arrangement of newspapers in any multiple of two within the capacity of the machine.

The location and relative arrangement of the cylinders with respect to one another may be varied without departing from the spirit of the invention, and in the drawings various arrangements are indicated, although it is to be understood that the invention is susceptible of embodiment in other arrangements not illustrated in the drawings or described in the specification.

In the drawings:

Figure 1 is a diagrammatic side elevation of a three-deck printing machine in which the cylinders of the middle deck and supplement perfecting unit are both adapted for half speed operation in the printing of supplements;

15 Fig. 13 is a detail showing the rollers employed to apply pressure to the web in passing over the former;

20 Referring to the arrangement shown in Figure 1, the frame of the machine is arranged in three decks, A, B, C, with a supplemental unit D at the rear.

25 The upper and lower decks A and C carry full speed perfecting units each comprising a pair of plate cylinders 20—20 with associated impression cylinders 21—21 and inking cylinders 22—22.

30 The arrangement of the perfecting units on decks A and C is of the usual type, the printing and impression cylinders being driven by suitable trains of gearing deriving power from a vertical centrally disposed shaft 23. It is not deemed necessary to illustrate the gearing employed for driving these 35 cylinders, which is of a character commonly employed in the art for a like purpose.

40 The cylinders of decks A and C are preferably of a length equal to the width of two newspaper pages plus margins, although said cylinders may be four pages wide in 45 length, and for purposes of description it may be assumed that said cylinders are in length equal to the width of two pages plus margins.

45 The intermediate deck B carries a perfecting unit comprising plate cylinders 24—24, impression cylinders 25—25, and inking cylinders 26—26.

50 The cylinders constituting the intermediate perfecting unit are precisely similar to those constituting the perfecting units on decks A and C, and the intermediate perfecting unit may be run full speed if desired, in which case it will function in precisely the same way as perfecting units on decks A and C. However, for the purpose of the present invention, the intermediate perfecting unit may be considered as a supplement printing unit having a capacity, by suitable adjustment of 55 gearing, to be driven at half speed, and to attain this result one of the impression cylinders 25 may be provided with a large spur pinion 27 which may be brought into mesh with a small spur gear 28 driven from the general train of gearing provided for driving the

perfecting units on the upper and lower decks, and when so driven the cylinders of the intermediate perfecting unit will rotate at approximately half speed, or slightly less be cut and delivered into the full speed webs fed through the intermediate cylinders may be cut and delivered into the full speed web from the upper and lower decks, with the result that the cut off supplement sections will register with every alternate web section of the full speed webs and thus constitute a supplement introduced into one section only of the completed newspaper.

70 The intermediate supplement printing unit of deck B may be employed to print a two-page wide web or a one-page wide web, depending upon whether a four-page or a two-page supplement is desired, but the machine of Fig. 1 makes special provision for the printing of a one-page wide two-page supplement by the use of mechanism which will now be described.

75 The perfecting unit carried by the rear extension D comprises but a single printing cylinder 29 of a length equal to the width of two pages plus margins, which printing cylinder co-operates with an impression cylinder 30 and an inking cylinder 31.

80 The supplement plate cylinder is plated with two sets of duplicate plates, the duplicate plates at one end of the cylinder being employed for the printing of one side of the two-page supplement, and the duplicate plates of the other end of the cylinder being provided for the printing of the opposite side 85 of the supplement web.

85 The one-page wide web 32 is led from the paper roll 33 over rollers 34 and 35, and between the plate cylinder 29 and impression cylinder 30, and thence over the roll 36 and 105 angle bars 37 and roll 38, which direct the web into register with the plates at the opposite end of the plate cylinder 29 and bring the previously unprinted side of the web into contact with the plates, so that both sides of 110 the one-page wide web will be perfected.

115 The supplement perfecting unit D may be driven by direct gear connection from the intermediate perfecting unit of deck B where the latter is being run at half speed, so that when thus driven both of the supplement perfecting units will run uniformly at half speed, but in cases where the perfecting unit of deck B is run at full speed the supplement perfecting unit D may be driven at half speed through the provision of a small pinion 39 and a large gear 40, the former of which derives its rotation from the gearing of deck B.

120 Where the supplement perfecting unit of deck D is being run at half speed to print a two-page half speed supplement sheet it will be necessary to plate the type cylinder 29 with duplicate pairs of plates, but it is also possible to run this perfecting unit at full speed for 130

the printing of two one-page wide supplement sheets adapted to be inserted one each into the respective sections of the completed newspaper, and where this is desired the plate cylinder 29 will be plated with four different or individual plates and run at full speed through direct full speed gear connection with the full speed gearing of the perfecting unit of deck B, in which latter case the one-page wide supplement web will be led full speed and associated with the two-page wide webs from the other decks and collected in conjunction therewith below the former, so that each section of the newspaper will contain a supplement perfected on the unit D.

It will thus be understood that the machine may be adjusted to print supplement sheets on either or both units B and D running each at half speed, or may be adjusted to print two single page wide supplement sheets on unit D running at full speed, depending upon the manner in which the perfecting units are entrained and employed, so that the machine is adapted to produce numerous variations in the character and manner of assembling of the completed product.

Attention will now be directed to the manner in which the supplement sheets are cut off and delivered into the bite of the full speed webs at the delivery end of the machine. This mechanism is shown in detail in Fig. 8.

The full speed webs from the upper and lower decks A and C are led over suitable rollers and delivered to the former 41 over the usual drag roller 42. The usual folding rollers 43 are located in advance of the former, and after leaving the rollers 43 the associated and folded webs are severed by the cutting cylinder 44, and the alternate lengths of web constituting one of the sections are caught by the retractile pins of the collecting roller 45 and carried around the roller in the usual manner and united with the oncoming web constituting the associated section of the complete newspaper in the manner common in prior machines operating upon the collecting principle.

The half speed supplement web 32, however, is passed between a pair of rollers 46, and thence between the supplement cutting cylinders 47 and 48 which are located above the drag roller 42, and are fed at approximately half speed, or slightly less, to conform to the speed of travel of the supplement web.

A supplement web from the perfecting unit of the intermediate deck B may also be led through the rollers 46 to the cutting cylinders 47 and 48 where the perfecting unit B is being used for half speed supplement printing, although, where said deck is being used for full speed printing, the web will be led over a roller 49 and associated with the other full speed webs on the drag roller 42.

The cutting cylinders 47 and 48 are posi-

tively driven through gearing which may be entrained to drive these cylinders either at half speed or full speed, depending upon whether the perfecting unit D is operated to print one supplement or two two-page supplements.

As shown in Fig. 8, the cylinders 47 and 48 are provided with spur gears 50 and 51, and where half speed is desired the cylinder 48 is driven through a large spur gear 52 meshing with a small spur pinion 53, which in turn meshes with a spur pinion at the far end of the shaft which carries the full speed spur pinion 54 meshing with the spur teeth 55 of a bevel pinion 56 meshing with a bevel pinion 57 on a shaft 58 in train with the main driving train for the machine.

Where it is desired to impart full speed to the cylinders 47 and 48, an intermediate spur gear 59 is entrained, and the small spur pinion 53 is thrown out of train so that the cylinders 47 and 48 can be readily adjusted either to operate at full speed or half speed.

Although the supplement driving is referred to as half speed, it will be found advantageous to so proportion the gears that the actual feeding travel of the supplement rollers and cylinders will be slightly less than half speed with the purpose in view of cutting the supplement sheets of a length slightly less than the length of the remaining pages of the newspaper sections to allow a slight margin of error in the positioning of the supplement sheets within the newspaper sections; and it will therefore be understood that where half speed is referred to it is the intention to include a speed which though slightly less approximates a half speed within the limits of variation required in properly positioning the supplement sheets within the newspaper sections.

Below the cutting cylinders 47 and 48 are located suitably driven brush rollers 60 and 61, the latter of which coacts with the underlying roller 49. The purpose of these brush rollers is to guide and advance the leading edge of the supplement web until it enters the bite of the full speed webs passing over the drag roller 42, at which instant the cutting cylinders 47 and 48 will act to sever the supplement sheet from the supplement web, so that the travel of the severed supplement sheet will be immediately accelerated and it will be carried forward at full speed with the webs between which it is interposed, and travel down over the former 41 and be properly inserted in the intended section as the latter is cut off below the former by the cutting cylinder 44.

In order to prevent the possibility of displacement of the severed supplement sheet after it has been inserted between the full speed webs and while it is passing over the former, a pair of suitably driven brush rollers 63 and 64 are provided which bear against

the center ridge of the former along the folding line of the web and serve to exert sufficient pressure against the edge of the inserted supplement sheet to prevent the latter from slipping out of registry with the full speed webs with which it is associated.

In order to provide for slight adjustment of the cutting cylinders 47 and 48 which may be required in order to properly gage the distance between such cylinders and the drag roller 42, the cutting cylinders, as shown in Fig. 9, are journaled within a slidable frame 65, suitably supported from the main frame of the machine, which sliding frame may be slightly raised or lowered through the action of an adjusting screw 66 having right and left screw threads 67 operating upon wedge blocks 68 and 69 which are interposed between the slidable frame 65 and an adjacent portion of the fixed frame of the machine. These wedge blocks act against the tension of springs 69 which bear against the slidable frame 65, and the adjustments required will not be in degree sufficient to interfere with the meshing of the driving train. Obviously other equivalent means might be provided for securing the intended adjustment.

As shown in Fig. 12, the carrier cylinder 48 which constitutes the female element of the cutting pair is provided with retractile pins 70 carried by a cam actuated arm 71 of the character commonly employed, which pins serve to momentarily engage the leading edge of the supplement web and carry it around the cylinder 48 until the leading edge is brought well under the pressure of the brush roller 60 after which the retractile pins will be drawn back and the web will proceed until it enters the bite of the full speed webs.

Immediately ahead of the brush roller 60 are located strippers 60^a between which the web runs to the second brush roller 61, below which are again located strippers 61^a which continue to control the forward edge of the web until it enters the bite of the full speed webs at the instant it is being severed from the half speed supplement web by the cutting action of the cylinders 47 and 48. After the full speed webs are brought together on the drag roller on top of the former, the supplement sheet will have to travel quite a distance between the webs from the top of the former to the folding rollers below the bottom of the former before there is sufficient pressure between the webs to control the leading end of the supplement sheet. The reason for this is because formers of the usual type at the present time are not made in such a way that they have any control of the supplement sheets where all the full speed webs are cut below the former unless tapes are employed.

In the present invention, the brush rollers are provided in the center of the former to put pressure on the webs running on the former with a two page supplement sheet be-

tween them, which has perfect control of the sheet at all times. With this device it will not be necessary to use any tapes on the former. The supplement sheets will register with the main pages and the press may be run at a high rate of speed.

Mention has already been made of the use of the brush rollers 63 and 64 which are located above the ridge of the former, but it is desirable to provide coacting rollers 63^a and 64^a located behind the ridge in the former and operating through center slots in the former, as indicated in Fig. 8, which shows the former partially broken away to reveal the rollers. These rollers may be driven by chain and sprocket mechanism 64^b, or in any other suitable manner.

One alternative method of applying pressure upon the ridge of the former is shown in Figs. 13 and 7, in which rollers 65^a are provided which are preferably of semi-hard rubber, or formed with a rubber or leather facing or the like, and each of such rollers is mounted on a depending adjustable bracket 65^b carried by an obliquely extending bar 65^m fixedly secured to the frame of the machine and supported above the ridge of the former, which may be adjusted to vary the pressure on the webs and supplement sheets.

The brackets 65^b are provided with slots 65^c, each slot receiving a boss 65^d which has screw threaded therein a pin 65^e carrying a washer 65^f, the outer end of the pin being unthreaded and reduced to receive the head of a handle 65^g which when inwardly positioned engages the threads and may be turned to exert pressure against the washer for clamping the bracket in adjusted position.

The downward adjustment of the bracket will be limited by a collar 65^h carried by a stud 65ⁱ projecting above the bracket, the collar being held in adjusted position on the stud by a set screw 65^j. This arrangement permits the pressure of the rollers to be individually adjusted, and at the same time permits the rollers to be readily lifted and thrown out of commission so as to afford space beneath the rollers for the threading of the webs, and the pins afford projections for lifting the rollers and brackets.

The rollers above described are not power driven, but, if desired, the arrangement shown in Fig. 6 may be employed, in which the roller shafts carry belt rollers 65^k which are driven by belts 65^l or the like.

Where it is desired to paste in the supplement sheets, a paster 72 is provided above the cutting cylinder 47, which paster is designed to act upon every alternate section of the upper full speed web, so that a strip of paste will be present along the folding line of those web sections which are to lie contiguous to the inserted supplement sheets. This requires a recurrent or interrupted action of the plaster which is secured by the engage-

ment of a roller 73 with an eccentric 74 carried by the shaft of the cutting cylinder 47.

The roller 73 is journalled upon an arm 75, and the paster is pivoted at the point 76, so that under the influence of the eccentric 5 the paster will be recurrently raised and lowered to bring the pasting roll 77 into contact with the overlying web. The roll is positively driven through the action of gears 78 10 and 79, the latter of which is mounted upon a shaft 80 which derives power through chain and sprocket connections 81 from a shaft 82, as shown in Fig. 11. This arrangement permits the paster roll 77 to rotate continually, but brings it only at recurrent intervals into contact with the under side of the overlying web.

The printing machine shown in Fig. 2 differs from the machine shown in Fig. 1 in 20 certain structural arrangements, although the principle of operation is quite similar. The machine of Fig. 2 provides two full speed perfecting units, each four pages wide, each perfecting unit adapted to carry sixteen 25 printing plates on each deck and to run at full speed. The machine also employs an eight page perfecting unit above the decks having cylinders in length equal to the width of four pages plus margins, and also employs in the rear a four page perfecting unit 30 having cylinders in length equal to the width of two pages plus margins.

In Fig. 2 the lower deck A' corresponds, save for the length of the cylinders, to the 35 deck A of Fig. 1, while the deck C' corresponds, save for the length of the cylinders, to the upper deck C of Fig. 1. The rear deck D' of Fig. 2 is two pages wide, and corresponds, in all respects, to the unit D of Fig. 1, 40 while the upper supplement perfecting unit B' is four pages wide, and corresponds, save for the length of the cylinders, to the deck B of Fig. 1. That is to say, the perfecting units carried by the decks A' and C' are the full speed perfecting units, while the units B' and D' are the supplement perfecting units.

The supplement perfecting unit D' is similar, in all respects, including the length of the cylinders, to the unit D first described, 50 and a special description thereof is not deemed necessary. The perfecting unit B', however, is similar in structure to the perfecting unit D', in that it employs but a single plate cylinder 83, but said cylinder is of a length equal to the width of four pages, which plate cylinder coacts with an impression cylinder 84 and inking cylinder 85.

Duplicate plates are employed for the 55 printing of a two page wide supplement sheet, and when thus plated the web 86 will be led around one end of the impression cylinder to receive the plate impressions at one end of the plate cylinder, and thence will be led over the angle bars 87 and reversed to receive on its opposite surface the impression

from the plates at the opposite end of the plate cylinder, after which it may be led to the supplement cutting cylinders 88 and 89, which correspond to the cutting cylinders 47 and 48 of the machine of Fig. 1. This lead of the web 86 as a two page wide supplement web is indicated in dotted lines at the right of Fig. 2, but the same web may be led through rollers 90 and 91 directly to the drag roller 92.

The supplement web 93 from the rear supplement perfecting unit D' is also led through suitable rollers to the supplement cutting cylinders 88 and 89, so that both half speed supplement sheets will be assembled, cut and inserted into the full speed webs in a manner in all respects similar to that heretofore described. The perfecting unit of deck B', being four pages in width, may, if desired, be employed as a full speed perfecting unit, in which case a two page wide web will be printed on one side and then perfected on the other at full speed by the plate cylinder 83.

Where thus used in conjunction with the full speed four page wide perfecting units of the two lower decks, and where the product is collected below the former, all three of the full speed perfecting units will be plated with individual plates, and the product collected into sections, while the two page wide supplement perfecting unit of Fig. 2 will be plated with duplicate plates and the half speed web cut off into two page wide supplement sections introduced into the alternate web sections composing the newspaper sections of the complete newspaper, the introduction of the supplement sheets being similar in all respects to that heretofore described, save for the fact that in dealing with a four page wide full speed web running from the decks A' and C', it will be necessary to split the web and run the divided section thereof over two formers, as indicated in Fig. 3, or in lieu thereof to carry one section of the web over angle bars 94 and associate it on one former, with the other section of the web in a manner well understood in the art. Of course, the supplement sheets from the half speed units B' and D' can both be delivered into one and the same newspaper section, so that they will enter said section in contiguous relation.

Fig. 4 shows a printing machine which is similar in all essential respects to the machines heretofore described, save for the fact that the three full speed perfecting units are arranged in vertically superposed relation in conjunction with one half speed supplement perfecting unit one page wide, the cylinders of which are arranged in superposed relation in advance of the full speed perfecting units and adjacent to the folding and cutting mechanisms. Two plate cylinders 29^a are employed in association with impression cylinders 30^a, and the supplement web is led from one couple

to the other to perfect both sides of the web. The machine of Fig. 5 differs from the machines heretofore described materially in the fact that in this machine all of the perfecting units are located close to the floor line. In this case, the perfecting units E and F are four pages wide full speed perfecting units each adapted to carry sixteen individual plates on the plate cylinders 95 and 96 which co-act respectively with impression cylinders 97 and 98.

The supplement perfecting unit G is arranged between the perfecting units E and F and comprises plate cylinders 99 and 100, which are preferably one page wide and which co-act with impression cylinders 101 and 102 in the printing of a one page wide supplement web 103. When operating at half speed the supplement perfecting unit will be driven through gearing 104 and 105, indicated in dotted lines in Fig. 5. In this arrangement, all of the perfecting units are driven through vertical shafts 106, 107 and 108 having bevel gear connection with a horizontal main driving shaft 109, although it is obvious that the method of driving the full speed and half speed perfecting units may conform to any method of driving well known in the present art. The supplement perfecting unit G when running at half speed and plated with duplicate plates will deliver the web to the supplement cutting cylinders 110 and 111, which will introduce a supplement into every other section of the full speed web, as indicated in full lines, but when the supplement perfecting unit G is running at full speed the web will be led to rollers 112 located beyond the cutting cylinders and delivered to the drag roller 42 above the former there to unite with the one division of the four page wide full speed webs.

In order that the adaptability of the machine of the present invention to the printing of newspapers in any multiple of two up to the full capacity of the machine may be clearly understood, I will now describe the various operations of the machine of Fig. 1 in the printing of variously constituted newspapers, with the understanding, however, that the operation of the other machines is essentially similar save for variations in capacity due to the number of perfecting units and the length of the cylinders. The description which now follows has reference to the printing of collecting runs from individual plates on the full speed perfecting units and with duplicate plates on the half speed supplement units.

A sixteen page paper: To print and fold a sixteen page paper, the first and second decks of the eight page perfecting units will be preferably used. The top deck of the press and the supplement perfecting units can be thrown out of commission. The two full speed perfected webs from the first and

second decks will be led to the drag roller and operating thus, there will be two eight page sections collected and folded together as one product, making a sixteen page paper.

An eighteen page paper: By using the lower and upper decks at full speed and the supplement perfecting unit D at half speed, a two page supplement will be introduced into the alternate full speed web sections, which will be collected into an eighteen page newspaper consisting of one eight page section and one ten page section.

A twenty page paper: By employing the upper and lower full speed decks with the middle deck operating at half speed, and plated with duplicate plates, a four page supplement will be introduced into alternate web sections and a twenty page paper produced consisting of two sections, one of eight pages and the other of twelve pages. A similar result can be accomplished by operating two of the main decks at full speed and operating the supplement perfecting unit of deck D also at full speed and plated with individual plates, in which case a two page supplement sheet will be introduced into each of the sections resulting in a newspaper consisting of two sections each of ten pages.

A twenty-two page paper: By operating the upper and lower main decks at full speed and the middle deck and supplement unit D each at half speed, a four page supplement and two page supplement will be introduced into one of the sections of the completed newspaper, which will result in a paper comprising one eight page section and one fourteen page section folded together as one product.

A twenty-four page paper: To produce a twenty-four page paper, the three decks A, B and C will all be run at full speed with individual plates, and will produce a newspaper consisting of two sections each constituting of twelve pages collected and delivered below the former. A similar result may be obtained by running the middle deck at half speed with duplicate plates, and the supplement deck D at full speed with the individual plates, in which case the single page wide web from the supplement perfecting unit D would be associated with the full speed webs below the half speed cutting cylinders, and this arrangement two page wide web from the middle deck would be carried through the half speed cutting cylinders, and this arrangement will result in a newspaper each section of which would include a two page supplement and alternate sections of which would also include a four page supplement, making two sections, one of fourteen pages and the other of ten pages.

A twenty-six page paper: To print and fold a twenty-six page newspaper, the three eight page decks of the press will run at full speed and the supplement perfecting unit

with duplicate plates will run at half speed and deliver a two page supplement sheet to every alternate section of the full speed webs resulting in a newspaper collected and folded to provide a twelve page section and a fourteen page section.

A twenty-eight page paper: To print and fold a twenty-eight page paper, the three eight page decks of the press will run at full speed, and the four page supplement perfecting unit D plated with individual plates will also run at full speed, and under this mode of operation, the knife and retractile pins of the cylinders 47 and 48 may be removed, and said cylinders driven at full speed, which will result in the collecting, folding and delivering of a newspaper consisting of two sections each of fourteen pages. Under another mode of operation, the one page wide supplement web will not run through the cylinders 47 and 48, but will be associated with the full speed perfected webs that are associated on the drag roller, which will also result in a newspaper consisting of two fourteen page sections.

It will be noted from the above that the present machine is designed when operating on the collect runs to print and fold newspapers in sections without skipping any product which constitutes a multiple of two pages up to the full capacity of the machine which is something greatly demanded by the publishers.

If it be desired to print and fold a book form paper, duplicate plates will be used, and where thus plated, the following products can be printed and folded in book form, namely, two, four, six, eight, ten, twelve and fourteen pages. Where book form newspapers are being produced, it is necessary to operate all of the perfecting units at full speed, since each page length of the webs will result in a complete newspaper, so that all of the constituent portions thereof must travel at the same speed.

Of course, where the printing machine employs cylinders of a length equal to the width of four pages, the capacity of the machine will be greater than that heretofore described, but the method of operating and the nature of the product under such conditions will be in all respects similar to that heretofore described, so that it is not deemed necessary to further discuss in detail the mode of operation of the machines illustrated in Figs. 2, 4 and 5. In each case the results are due to the provision of supplement perfecting units capable of being run at half speed for the purpose of introducing supplement sheets into alternate sections of the full speed web in the manner heretofore described, and this capacity, joined with the capacity for full speed operation of the supplement perfecting units, enables the requisite number of pages to be

introduced as supplements in order to give to the machine the variable capacities for printing in all multiples of two up to the maximum capacity of the machine.

Moreover, in the printing of the various products, the machine of Fig. 1 in each instance will be operated with no idle cylinder surface; that is to say, each plate cylinder in operation will carry its full complement of plates so that all portions of the associated impression cylinders will be brought into action and the inking mechanisms will function in the normal way, which is important, in that it avoids the objection due to inequality in the beating down of the blankets and wear on the impression cylinders when the plate cylinders are partially plated, and also avoids special adjustments of the ink fountains which is required when the plate cylinders are operated with less than the full complement of plates.

The reduced speed gearings being located on the far side of the machine, and constituting a train separate from the full speed gearing, may be given any tooth ratio desired to feed the supplement webs either as half speed or less than half speed, as occasion may require.

The method here involved is applicable to numerous types of printing machines which operate on the collecting principle, and, of course, the location and method of driving the supplement perfecting unit or units can be varied in conformity with any structural or motive principle desired without departing from the spirit of the invention, so that numerous variations in these details is contemplated, and it will be understood that the various modifications shown are merely by way of exemplifying the basic principle of operation hereinbefore illustrated and described.

I claim:

1. In a printing machine, the combination of a main cylinder perfecting unit in length equal to the width of a plurality of pages, means for driving the main unit at full speed, a supplement cylinder perfecting unit in length equal to the width of two pages, means for driving the supplement perfecting unit either at full speed or partial speed, a former, a drag roller located at the rear end of the former, supplement cutting cylinders behind the drag roller and adapted to cut the supplement sheet when traveling at partial speed at the instant its leading end comes into the influence of the drag roller, roller means exerting pressure along the ridge of the former to hold the supplement sheet in registering relation with the adjacent section of the full speed web, and collecting mechanism below the former, substantially as described.

2. In a printing machine, the combination

of a main cylinder perfecting unit in length equal to the width of a plurality of pages, means for driving the main unit at full speed, a supplement cylinder perfecting unit in length equal to the width of two pages, means for driving the supplement perfecting unit either at full speed or partial speed, a former, a drag roller located at the rear end of the former, supplement cutting cylinders behind the drag roller and adapted to cut the supplement sheet when traveling at partial speed at the instant its leading end comes into the influence of the drag roller, roller means exerting pressure along the ridge of the former to hold the supplement sheet in registering relation with the adjacent section of the full speed web, said roller means including co-acting rollers located inside and outside of the former in adjacent relation to the ridge thereof, and collecting mechanism below the former, substantially as described.

3. In a printing machine, the combination of a main cylinder perfecting unit in length equal to the width of a plurality of pages, 25 means for driving the main unit at full speed, a supplement cylinder perfecting unit in length equal to the width of two pages, means for driving the supplement perfecting unit either at full speed or partial speed, a former, a drag roller located at the rear end of the former, supplement cutting cylinders behind the drag roller and adapted to cut the supplement sheet when traveling at partial speed at the instant its leading end comes 35 into the influence of the drag roller, roller means exerting pressure along the ridge of the former to hold the supplement sheet in registering relation with the adjacent section of the full speed web, collecting mechanism 40 below the former, and roller means and stripers located between the supplement cutting rollers and the drag roller for guiding the leading edge of the supplement web prior to its engagement by the drag roller, substantially as described.

4. In a machine of the class described, the combination of a plurality of full speed perfecting units and means for driving the same at full speed, a supplement perfecting unit 50 and means for driving the same at slightly less than half the surface speed of the full speed perfecting units, supplement cutting cylinders co-operating with the supplement perfecting unit and means for driving the same at the same surface speed as the supplement perfecting unit, a main cutter, and means for rotating the same at full surface speed, the supplement cutter being adapted to cut a two page supplement sheet slightly 55 shorter than the main sheets cut by the main cutter, substantially as described.

5. In a machine of the class described, the combination of main perfecting units and means for driving the same at full speed, a four page supplement perfecting unit and

means for driving the same, a supplement carrier cylinder having retractile pins adapted to be protruded beyond the surface of the cylinder and be retracted below said surface, and roller means co-operating with the carrier cylinder and having a yielding surface and adapted to control the leading end of the supplement sheet when stripped from the carrier cylinder by the retraction of the pins, substantially as described.

6. In machine of the class described, the combination of a supplement cutting device comprising cutting and carrier cylinders adapted to make a clean cut for each rotation of the supplement cutting device, a former, rotary folder and main cutting and collecting mechanism co-operating with the supplement cutting cylinder, the relation of the parts being such as to result in the cutting of supplement sheets slightly shorter than the main sheets, and means for associating the cut off supplement sheets with the main sheets, substantially as described.

7. In a machine of the class described, the combination of two full speed perfecting units including plate cylinders with column circumferential to the plate cylinders, a former, forwarding means adjacent to the former, means for leading two full speed perfected webs from said perfecting units to the forwarding means, supplement perfecting means including a plate cylinder providing an area for four plates, means for driving said cylinder at a slower speed than the full speed perfecting units, a supplement cutting device, means for driving said cutting device at the same surface speed as the supplement perfecting means, means for leading a one page wide supplement web from the supplement perfecting means to the supplement cutting device, means for leading the supplement web from the supplement cutting device to the forwarding means adjacent to the former and introducing the same between the two full speed perfected webs running over the former, a plurality of pressure means on the center of the former adapted to hold each cut off supplement sheet in the proper position between the full speed webs to maintain registry of the supplement sheets while running down over the former, substantially as described.

8. In a machine of the class described, the combination of a plurality of full speed main perfecting units having cylinders in length equal to the width of a plurality of pages, means for driving said perfecting units at full speed, an eight page supplement perfecting unit and a four page supplement perfecting unit, means adapted to drive each of the supplement perfecting units at the same speed as the full speed perfecting units or at a slower speed, a former, two page wide supplement cutting cylinders above the former, means for driving said cylinders at

the slower speed of the supplement perfecting units, and a main cutter and collecting device below the former, substantially as described.

9. In a machine of the class described, the combination of supplement cutting and carrier cylinders, the carrier cylinder being provided with retractile pins adapted to control the leading end of the supplement sheet and means for actuating said pins, a roller having a yielding contact surface co-operating with the carrier cylinder to act upon the leading end of the supplement sheet when the pins are retracted inside the cylinder, a full speed forwarding means, strippers positioned to guide the supplement sheet toward the full speed forwarding means, a former, and supplement sheet controlling means on the former to hold the cut off supplement sheets in position, substantially as described.

10. In a machine of the class described, the combination of a main perfecting unit, supplement cutting cylinders, means for driving said cylinders at a slower speed than the speed of the main perfecting unit, one of the cutting cylinders being provided with retractile pins and means for actuating the same, a roller co-operating with the latter cylinder for guiding the leading end of the supplement sheets, full speed forwarding rollers, strippers positioned to guide the supplement sheets to the full speed forwarding rollers, a former, adjustable rollers in the center of the former adapted to run at the same surface speed as the main perfecting units to control the supplement sheets running at full speed over the former, substantially as described.

11. In a machine of the class described, the combination of a main perfecting unit and associated main web feeding devices and means for operating the same at full speed, a supplement unit and associated web feeding devices and means for operating the same at a reduced speed, means for cutting off sections of the supplement web to constitute supplement sheets, means for bringing the cut off supplement sheets into register with alternate sections of the full speed web, a pasting device in proximate relation to the supplement sheet cutting means, connections between said supplement sheet cutting means and said paster for bringing the latter into acting relation with the full speed web for applying paste to every other section thereof prior to the association of the supplement sheets with the main web to bring the supplement sheets into register with the pasted sections, and means for applying pressure to the main web and the inserted supplement sheets along the pasting line, substantially as described.

12. The combination of a printing, inserting, and folding machine, comprising a plurality of full speed perfecting units, a plural-

ity of pages in width having columns circumferential to the plate cylinders, a four-page supplement perfecting unit adapted to run at slightly less than half the surface speed of the full speed perfecting units, a supplement cutting device adapted to run at the same surface speed as the four-page supplement perfecting unit, a forwarding device, means for leading a plurality of full speed perfected webs or web members to the forwarding device, means for leading a one-page wide perfected web from said four-page supplement perfecting unit to the supplement cutting device, means for inserting two-page supplement sheets between the full speed webs or web members with the supplement pages in registry with the main pages, and with less margin at either end of the columns of the supplement sheets than those of the main pages, substantially as described.

13. The combination of a printing, inserting, and folding machine comprising a plurality of full speed perfecting units, a plurality of pages in width having columns circumferential to the plate cylinders, two supplement perfecting units adapted to run at approximately half the surface speed as the full speed perfecting units, a supplement cutting device adapted to run at the same surface speed as the supplement perfecting units, means for leading a plurality of full speed perfected webs or web members to a forwarding device, means for leading a two-page wide web or web member to the supplement cutting device, means for leading a one-page wide web or web member to the same cutting device, means for severing a four-page sheet and a two-page sheet, and means for inserting the four-page sheet and the two-page sheet between the full speed webs or web members, substantially as described.

14. In a printing, inserting, and folding machine of the class described, with columns circumferential to the plate cylinders, adapted to perfect a plurality of full speed webs or web members, an eight-page perfecting means adapted to run at full speed or slower speed, a four-page perfecting means adapted to run at full speed or slower speed, a former co-operating with said printing machine, a supplement cutting and inserting device adjacent to said former and adapted to run at slower speed, and main cutting, collecting, and folding devices below said former, said mechanisms being effective to print and fold a newspaper, starting with two pages and increasing by two pages up to the full capacity of the printing machine.

15. A newspaper printing machine, comprising full speed perfecting means, a former co-operating with said perfecting means, full speed cutting and collecting means below said former, adapted to make two cuts for each revolution of the full speed perfecting means, a supplement perfecting means hav-

ing a plate area of only four plates and adapted to operate at full speed and a slower speed, a supplement cutting cylinder and supplement carrier cylinder geared together and operating at the same speed as the supplement perfecting means when operating at the slower speed, said cylinders arranged between full speed webs or web members which are associated above said former, said cylinders operating back of said former, said cylinders being further equipped with adjusting means for decreasing or increasing the distance of said cylinders from said former, an inserting device between said carrier cylinder and said former, means for cutting and inserting two-page supplement sheets between and in register with the main pages that are folded on said former, means for collecting the said two cuts with a two-page supplement sheet in one of the said cuts, a second folder means below said former, adapted to fold together the said collected cuts, said mechanisms being effective to print and fold a newspaper, starting with two pages, and increasing by two pages, up to the full capacity of the printing machine.

16. A newspaper printing machine, comprising a plurality of full speed perfecting means, a former co-operating with the full speed perfecting means, full speed cutting, collecting and folding devices below said former, a supplement perfecting means having an area of four plates, adapted to operate at full speed and at a slower speed, said supplement perfecting means being mounted on a frame back of said full speed perfecting means, and adjacent to paper rolls, supplement cutting and inserting devices above said former geared to operate at the same speed as the supplement perfecting means when operating at the slower speed, said supplement cutting and inserting devices being arranged between full speed perfected webs which are folded on said former, said mechanisms being effective to print and fold a newspaper, starting with two pages, and increasing by two pages, up to the full capacity of the printing machine.

17. In a printing machine of the class described, comprising a first folder device, a pair of supplement cylinders adapted to operate at a slower speed, mounted on a frame above said first folder device, the top cylinder of the said pair having cutting means, and the bottom cylinder of said pair having sheet carrying pins adapted to carry cut sheets part way around said cylinder; a sheet forwarding means operating on the outside of said bottom cylinder, adapted to control the cut sheets at a point where the carrying pins do not carry said sheets, and means for guiding said sheets away from the said bottom cylinder, to run downward between inserting means, to full speed forwarding means, where said sheets will start to run at full

speed between the full speed perfected webs, said pair of supplement cylinders being further equipped with adjusting means adapted to move both of said cylinders up or down.

18. A printing machine of the class described, comprising a former, a pair of supplement cylinders geared to operate at a reduced speed, said cylinders being mounted on a frame above said former, the top cylinder of said pair having cutting means, the bottom cylinder of said pair being equipped with sheet carrying pins and sheet forwarding means on the outside of said cylinder, sheet inserting full speed forwarding means below said bottom cylinder and said forwarding means on the outside of said cylinder, and a former below said full speed forwarding means, the said pair of supplement cylinders being further equipped with adjusting means for moving both of said cylinders up or down.

19. In a printing, inserting and folding machine of the class described, with columns circumferential to the plate cylinders, a plurality of full speed eight-page perfecting means, a perfecting means having a plate area of eight plates adapted to operate at full speed and a slower speed, a supplement perfecting means having a plate area of four plates adapted to operate at full speed and a slower speed, a former co-operating with the above named perfecting means, full speed cutting, collecting and folding devices below said former, a pair of supplement cylinders, one of said cylinders having cutting means, and the other cylinder of said pair being equipped with sheet carrying means, said pair of cylinders being geared to operate at a slower speed, inserting means between said pair of cylinders and said former, said mechanisms being effective to print and fold a newspaper starting with two pages, and increasing by two pages, up to the full capacity of the printing machine; any or all of the above perfecting means, when in operation, having no idle plate or impression surfaces on any of the above combinations, at the option of the operator.

20. A newspaper printing, inserting and folding machine of the class described, comprising a plurality of eight-page full speed perfecting units, a supplement perfecting means having an area of only four plates geared to operate at full speed and a slower speed, said perfecting means being mounted on a frame back of said perfecting units and located between the webs that run to said perfecting units, said perfecting means being further equipped with two angle bars adapted to give the one-page-wide two quarter turns after the web is printed on one side by two plates on one end of the plate cylinder, and means for perfecting the reverse side of the web after turning the web over said angle bars by two plates on the other end of the

- same plate cylinder, a former co-operating with said perfecting units and said perfecting means, full speed cutting, collecting and folding devices below said former, supplement cutting means back of said former, geared to operate at the same speed as the supplement perfecting means when operating at the slower speed, and an inserting device between said cutting means and said former.
21. The combination of the class described, comprising three eight-page perfecting units mounted on frames on different levels, the bottom and top units geared to operate at full speed, the middle unit geared to operate at full speed and a slower speed, a supplement perfecting means having an area of only four plates geared to operate at full speed and a slower speed, said perfecting means being mounted on a frame back of the said perfecting units, an inside roll support underneath said perfecting means, roll supports on different levels and back of the said inside roll support, a former co-operating with said perfecting units and said perfecting means; full speed cutting, collecting and folding devices below said former, supplement cutting means arranged between full speed webs which are associated above said former, said supplement cutting means geared to operate at the same speed as the supplement perfecting means when operating at the slower speed, an inserting means between said supplement cutting means and said former, said mechanisms being effective to print and fold a newspaper starting with two pages, and increasing by two pages, up to the full capacity of the printing machine, any or all of the above perfecting means, when in operation, having no idle plate or impression surfaces, on any of the above combinations, at the option of the operator.
22. The combination of a former, a pair of cutting cylinders back of said former geared to operate at a reduced speed, one of the cylinders of the pair being equipped with cutting means, the other cylinder of the same pair being equipped with knife-cutting slot and sheet carrying pins; an inserting means between said cutting cylinders and said former, said cylinders being further equipped with adjusting means adapted to move the said pair of cutting cylinders at the same time, to increase and decrease the distance of said cylinders from said former.

JOHN A. BOYCE.
